UNITED STATES PATENT OFFICE.

JAMES T. POKORNY, OF CEDAR BAYOU, TEXAS, ASSIGNOR OF ONE-THIRD TO A. T. EDDINGSTON, OF PORT ARTHUR, JEFFERSON COUNTY, TEXAS.

CLAY-DIGGING MACHINE.

Application filed April 22, 1920. Serial No. 375,837.

To all whom it may concern:

Be it known that I, JAMES T. POKORNY, citizen of the United States, residing at Cedar Bayou, in the county of Harris and 5 State of Texas, have invented certain new and useful Improvements in a Clay-Digging Machine, of which the following is a specification.

This invention relates to new and useful 10 improvements in a clay digging machine.

One object of the invention is to provide a machine of the character described which is specially adapted for the purpose of digging clay to be used in the formation of 15 brick, tile and the like.

Another object of the invention is to provide a machine of the character described by means of which clay of a character adapted to be used in making brick, tile and the 20 like, may be dug and partially pulverized, preparatory to molding the same.

Another object of the invention resides in the provision of means whereby the machine may be propelled along a track in either 25 direction so as to bring the saws against the work.

With the above and other objects in view, the invention has particular relation to certain novel features of construction, operation 30 and arrangement of parts, an example of which is given in this specification and illustrated in the accompanying drawings wherein,

Figure 1 is a plan view of the machine,

Figure 2 shows a side elevation of a pair 35 of beveled pinions employed in connection with the means for shifting them,

Figure 3 shows a side view of the machine and

Figure 4 shows a transverse sectional view 40 taken on the line 4, 4 of Figure 3.

Referring now more particularly to the drawings wherein like numerals of reference 45 designate similar parts in each of the figures, the numerals 1, 1 refer to the rails of a stationary track. The numerals 2, 2 designate the rear tractor wheels which are flanged in the usual way to travel along said track. Front carrier wheels are also provided, but are not shown in the drawings. The tractor wheels 2 are fixed upon the respective ends of an axle 3 which is rotatable 50 in the bearings 4, 4 and fixed upon said axle is a sprocket wheel 5. Mounted upon the front and rear axles is a frame work 6 which

supports the motor 7. This motor has the usual drive shaft 8 and fixed upon one end thereof there is a pulley 9 over which the drive belt 10 operates. Rotatably mounted in suitable bearings 11, 11 carried by the 60 opposite side of the frame work there is a counter shaft 12 and fixed thereon is a pulley 13 over this belt the belt 10 operates, and through which said pulley is driven. The shafts 12 has a spool 14 splined thereon, 65 whose respective ends are formed with beveled pinions 15, 15. Rotatably mounted in suitable bearings 16, 16 carried by the frame work, and extending at right angles to the shaft 12 there is a shaft 17 whose forward 70 end has the beveled pinion 18. A manual lever 19 is provided which is connected to the spool 14 and through which said spool may be shifted to bring the pinions 15 into mesh with the pinion 18 alternatively. Fas- 75 tened to the adjacent side of the frame work there is a bracket 20 formed with three notches as 21 which are spaced apart. When the spool 14 is shifted into any particular position the lever 19 may be engaged in the 80 corresponding notch 21 to hold said spool in set position. When one of the pinions 15 is in mesh with the pinion 18 the shaft 17 will be driven in one direction and when the other pinion 15 is in mesh with said pinion 85 18 the shaft 17 will be driven in the opposite direction. Said spool 14 may be also shifted to neutral position as shown in Figure 1 and the shaft 17 will thereby be disconnected from the motor. Aligned with the sprocket 90 wheel 5 there is a sprocket wheel 22 which is fixed upon the shaft 17 and operating over said sprocket wheel there is a sprocket chain 23 through which the rear axle 3 is driven and by means of which the entire machine 95 may be propelled along said track either forwardly or reversely.

Rotatably mounted in suitable bearings 24, 24 carried by the side of the frame work there is a counter shaft 25 which is in alignment 100 with the shaft 12 and which is arranged to be clutched therewith and unclutched therefrom through the clutch 26, which is controlled in the usual way by means of the clutch lever 27. The outer end 105 of the shaft 25 has a spool gear 28 fixed thereon.

A boom is provided which is formed of the channel irons 29, 29 spaced a suitable distance apart and tied together by means of 110

suitable cross bars 30. The inner ends of these channel irons have bearings on the shaft 25. The spur gear 28 is in mesh with a larger spur gear wheel 30' which is fixed 5 upon the corresponding end of transverse shaft 31 which is rotatably mounted in suitable bearings in the side members of said boom and there is a roller 32 fixed upon the shaft 31 between said side members. At the 10 free end of the boom are the bearings 33, 33 in which the free shaft 34 is rotatably mounted and fixed upon this shaft between the side members 29 there is a gang of pulverizing saws 35. Fixed upon one end of the shaft 34 there is a pulley 36 which is in 15 alignment with a similar pulley 37 which is fixed upon the end of the shaft 25 and operating over these pulleys and transmitting rotation from the latter to the former there 20 is a belt 38 through which the saws are rotated. Fixed upon the other end of the shaft 34 outside of the corresponding side member 29 there is a digging saw 39 which operates against the breast of the work and cuts the 25 clay loose and delivers it within the reach of the gang saws 35 by means of which the clay is pulverized.

Fastened to the respective side members 29, 29 are the side plates 40, and 41 which 30 depend below the boom and which have the respective bearings 42, 42 in which the transverse shaft 43 rotates. This shaft has roller 44 fixed thereon and a bent conveyor 45 operates over the respective rollers 32 and 44. 35 The outer end of this conveyor is arranged closely adjacent the gang saws underneath and the pulverized clay is delivered on to said conveyor by said saws and is carried upwardly by the conveyor and discharged into 40 the depending hopper 46 which is secured to the adjacent side of the frame work and which delivers the material on to a suitable conveyor as 47 by means of which the material is delivered to the desired place. Up- 45 standing from the side of the frame work, adjacent the boom, are the standards 48, 48 which are spaced apart and between the upper ends of which the lever 49 is pivoted. One end of this lever is connected to the free 50 end of the boom through the link 50 and the other end thereof has a counter balance weight 51 attached thereto.

The standards 48 are suitably placed by

means of the braces 52, 52 which are fastened at their lower ends to the frame work 55 and at their upper ends to the respective standards. These braces have suitable aligned bearings in which the shaft 53 rotates and fixed upon said shaft between said braces is a drum 54 a cable 55 is wound around the drum and has its respective ends secured to the lever 49 on opposite sides of the standards 48. One end of the shaft 53 has a crank 56 secured thereto by means of which the drum 54 may be rotated and the boom thereby elevated or lowered. This may be easily accomplished with little effort by reason of the fact that the boom is counterbalanced by the weight.

What I claim is:

1. A device of the character described including a frame work, a boom pivoted thereto at one end, a gang of pulverizing saws rotatably mounted at the free end of said boom, a digging saw spaced from said pulverizing saws, an operative mechanism carried by the frame work through which said saws may be driven, means for elevating and lowering the same, depending side plates carried by the boom, an endless belt moving 75 between the side plates, said belt and plates forming a conveyor disposed to receive from said saws.

2. A device of the character described including a frame work, a boom pivoted thereto at one end, a gang of saws rotatably mounted at the free end of said boom, an operative mechanism carried by the frame work through which said saws may be driven, depending side plates carried by the 80 boom, an endless belt between said plates driven by said mechanism and forming with said plates a conveyor arranged to receive the material from the saws, a delivery conveyor disposed to receive from the first mentioned conveyor, and a hopper through 85 which the material is discharged from the former conveyor to the latter.

In testimony whereof I have signed my name to this specification in the presence of 100 two subscribing witnesses.

JAMES T. POKORNÝ.
